United States Patent Office

Des. 215,896
Patented Nov. 4, 1969

215,896

COMBINED SIGN AND HOLDER THEREFOR

William E. Moore, 1093 Colonial Ave.,
Andalusia, Pa. 19020

Filed Jan. 30, 1969, Ser. No. 15,568

Term of patent 14 years

Int. Cl. D29—99

U.S. Cl. D72—1

FIG. 1 is a front perspective view of the combined sign and holder therefor in the upright position;

FIG. 2 is a rear elevational view of the combined sign and holder therefor, the side shown not being visible in FIG. 1; and

FIG. 3 is a perspective view from the rear of the combined sign and holder therefor in folded position.

I claim:

The ornamental design for a combined sign and holder therefor, as shown.
